UNITED STATES PATENT OFFICE

SAMUEL E. SPERRY, OF HOLLIS, NEW YORK, ASSIGNOR TO INTERTYPE CORPORATION, OF BROOKLYN, NEW YORK, A CORPORATION OF NEW YORK

AUTOMATIC RECASTING CONTROL FOR TYPOGRAPHICAL MACHINES

Application filed August 25, 1930. Serial No. 477,712.

The present invention relates to improvements in typographical machines of the general class shown and described in U. S. Letters Patent No. 436,532, granted September 16, 1890, to O. Mergenthaler, wherein matrices stored in a magazine are delivered therefrom selectively under control of a keyboard and are assembled, together with spacers, into lines which are presented before a mold and type bars or slugs are cast therefrom, each assembled line of matrices and spacers being usually presented once to the mold for the casting of a single type bar or slug therefrom, after which the matrices and spacers comprising the line are distributed or returned to their places of storage ready for reuse.

The primary object of the present invention is to provide simple and easily set means whereby any one or more of the assembled lines of matrices and spacers can be presented to the mold a plurality of times in succession to cast a plurality of duplicate or similar type bars or slugs therefrom automatically or without the necessity of setting the machine into operation through manual movement of the usual controlling lever each time the line is presented for a cast.

A further object of the invention is to provide recasting means for machines of this class which is capable of being set selectively to cause the machine to operate through any predetermined or desired number of casting cycles, according to the number of similar type bars or slugs to be cast.

To these and other ends, the invention consists in certain improvements and combinations and arrangements of parts all as will be hereinafter described, the features of novelty being pointed out particularly in the claims at the end of this specification.

In the accompanying drawings:—

Fig. 1 is a front elevation of a portion of a typographical machine provided with automatic recasting control means embodying the present invention;

Fig. 2 is a top plan view on an enlarged scale of the line receiving jaws of the first elevator and the recasting control means;

Fig. 3 represents a vertical section taken on the line 3—3 of Fig. 2, showing the first

elevator jaws at the normal matrix line receiving level and showing the recasting control means set in position for operation;

Fig. 4 is a view similar to Fig. 3 but showing diagrammatically the manner in which the recasting control means is thrown out of operation, after the desired number of casts have been made;

Fig. 5 represents a horizontal section taken on the line 5—5 of Fig. 1, showing the controlling connection between the recast control means and the starting and stopping means for the machine;

Fig. 6 is a detail view of the device which determines the number of slugs which will be cast during each casting operation, the device in this instance containing three pins to produce three casts from each matrix line;

Fig. 7 is a perspective view showing the recasting mechanism applied to the driving means for the first elevator; and

Fig. 8 is a detail sectional view on an enlarged scale, showing the manner of removably mounting the pins in the device which determines the number of casts which will be made.

Similar parts are designated by the same reference characters in the several figures.

The present invention is applicable generally to typographical machines of the class in which, during normal operation of the machine, a cast is made from each line of assembled matrices and spacers after which the matrices and spacers composing the line are distributed or returned to their usual places of storage, following which another cast is made from another or different assembled line of matrices and spacers, so that one type bar or slug will ordinarily be cast for each line of matrices and spacers assembled in the machine. The Mergenthaler patent hereinbefore referred to shows and describes a machine of that class, and the present invention is shown applied to a machine of the type shown in said patent. While the preferred embodiment of the invention is shown in the present instance, it will be understood that the invention is not restricted to the precise construction shown since equiv-

alent constructions are contemplated within the scope of the claims.

In the present instance, 1 represents the usual so called assembling elevator in which the matrices and spacers to form each line are assembled, 2 represents the usual so-called delivery channel, 3 represents the usual so-called first elevator having front and rear jaws 4 and 5 to receive the assembled line of matrices and spacers between them and to present the line to the usual mold for casting the type bar or slug therefrom, the first elevator being guided as usual to reciprocate vertically in a so-called vise frame 6, 7 the cap 7 of the vice frame having the usual vise jaws 8 and 9 between which the line of matrices and spacers is clamped endwise while presented in casting position in front of the mold, and 10 represents the usual so-called delivery slide which reciprocates in a guide 11 and serves to transfer each assembled line of matrices and spacers from the assembling elevator to the first elevator while the latter is in its normal position as shown in Fig. 1. 12 represents the usual so-called transfer slide which operates, while the first elevator is in its uppermost position, to remove the line of matrices and spacers from the first elevator, after a cast has been made from such line, to the usual transfer channel 13 from which the matrices are lifted in the usual and well known manner for distribution into the magazine from which they were drawn and spacers are returned to the usual space band box 14. The delivery slide 10 is operated by a lever 114 and the first elevator is reciprocated by a lever 15 which is connected to the first elevator through the medium of the usual spring cushion 16.

40 The first elevator and the delivery and transfer slides, in machines of this type, are operated in the proper sequence by a main cam shaft 100 which causes a cam 101 co-operative with the lever 15 to operate the first elevator; the cam shaft as is well known, being driven through the gears 102 from the main clutch 103 of the machine and, during the normal operation of the machine, is stopped, after completing each revolution 50 representing a complete cycle of operations, by the engagement of a pawl 18 pivotally mounted on a cam 17 carried by the cam shaft with the usual vertical stop pawl 19 which is mounted on a vertical shaft 20 and controls the main clutch, a starting pawl 21 rotatable on the shaft 20 being arranged to dislodge the pawl 18 from the stopping pawl 19 and thereby cause engagement of the main clutch and rotation of the main cam shaft 55 to initiate the next cycle of operations. The starting pawl 21 is connected to a dog 22 which bears upon a pin 23 carried by a forwardly and rearwardly reciprocatory bar 24 which acts on the clutch controlling lever 104 and is connected to the usual starting

lever 25 by a toggle 26, pulling of the starting lever 25 forwardly or into the position shown in Fig. 5 causing the starting pawl 21 to dislodge the pawl 18 from the stopping pawl 19 and thereby setting the main cam shaft of 70 the machine into operation, after which the starting lever 25 usually returns to its normal rear position so that the pawl 18 carried by the cam 17 will engage the stopping pawl 19 and cause disengagement of the main 75 clutch of the machine and stopping of the main cam shaft after the latter has completed a revolution or has performed a complete cycle of operations. The construction and mode of operation of the starting and 80 stopping means and its relationship with the main clutch of the machine and the construction and mode of operation of the main cam shaft and its operating connections with the first elevator and the line delivery and transfer slides may be substantially as disclosed in the Mergenthaler patent hereinbefore referred to and U. S. Patent No. 1,194,937, granted Aug. 15, 1916, to W. E. Bertram, to which reference is made for a detailed explanation of these parts of a machine of this 85 class.

The means provided by the present invention for enabling a plurality of similar type bars or slugs to be cast from any assembled line of matrices comprises, as shown in the present instance a lever 27 which is pivoted intermediately of its ends to the front of the vise cap 7 by a screw or other pivot 28, its upper end extending to a position in front of the line delivery slide 10 and forward of the path of the front jaw 4 of the first elevator and its lower end extending preferably to a point near the lower end of the vise frame 6. The short line transfer finger 10^a of the line delivery slide carries an arm 29 which is pivoted thereon as by a pivot screw 30 so that this arm may swing forwardly into a position which will bring it into the path of the lever 27 as shown in Fig. 2, or said arm may be 100 swung upwardly into a position where it will clear the lever 27, a spring-pressed locking detent 30^a being provided for holding said arm in operative position. When the arm 29 is set in the operative position so that it projects forwardly from the line delivery slide, it will engage the upper end of the lever 27 during the final portion of the line transfer movement of said slide and will swing the lever 27 from its normal position as shown by the dotted lines in Fig. 1 into the full line position shown in that figure, but when the arm 29 is swung upwardly into an inoperative position, the lever 27 will be unaffected by the movement of the line delivery slide.

The lever 27 is pivotally connected at a point below its pivot 28 to a link 31 and this link is pivotally connected to the middle pivot 32 of a toggle composed of links 33 and 34, the toggle link 33 pivotally engaging the 130

pivot 35 on which the starting lever 25 is mounted and which slidably guides the bar 24, and the link 34 having a slot 34^a at its forward end which pivotally engages a pivot 5 pin 36 which is fixed to an extension 37 which projects forwardly from the starting bar 24 so that the toggle links 33 and 34 will not be straightened by the pulling forward of the starting lever 25. While the lever 27 occupies 10 its normal position as shown by dotted lines in Figs. 1 and 5, the toggle links 33 and 34 will be in the flexed or broken position as shown by the dotted lines in Fig. 5, but movement of the lever 27 into the full line position 15 shown in Figs. 1 and 5 will straighten or lock the toggle links as shown by the full lines in Fig. 5, thereby locking the starting bar 24 in its forward position after being pulled forward by the starting lever 25 and holding 20 the starting pawl 21 in a position to prevent lodging of the pawl 18 on the stopping pawl 19 so that the cycle of operations of the machine will be repeated. While the toggle links 33 and 34 are flexed as shown by the 25 dotted lines, the starting pawl 21 will clear the pawl 18 so that the latter will engage the stop pawl 19 and thus arrest the operation of the machine after it completes a cycle of operations, but while the toggle links 33 and 34 30 are in straightened or locked position as shown by the full lines in Fig. 5, the starting pawl 21 will be held in the path of the pawl 18 so that the latter will pass the stopping pawl 19, so that the main cam shaft and the 35 mechanism operated thereby will continue in operation, after a cycle of operation has been completed.

Means is provided for automatically stopping the machine after the desired number 40 of casts have been made from an assembled line of matrices and spacers. Such means as shown in the present instance comprises a toothed or ratchet wheel 38, a shaft 39 to which such ratchet wheel is fixed, said shaft 45 being rotatably mounted in the upper end of the lever 27 and provided at the forward side thereof with a knurled head or handle 40 by means of which it may be rotated to set it, and the shaft 39 carries a suitable number 50 of pins 41 which are threaded or otherwise removably mounted therein and project radially therefrom as shown in Fig. 8, these pins and the ratchet wheel 38 being preferably arranged at the rear side of the lever 55 27 as shown in Fig. 2 and in front of the path of vertical movement of the front jaw 4 of the first elevator. A latch 42 is pivoted on the rear side of the lever 27 by the pivot pin 43, and one end of this latch is connected 60 to a tension spring 44, the other end of this spring being attached to a pin 45 which is fixed to the rear side of the lever 27. The other end of the latch 42 projects into the path of a pin 46 which is fixed to and projects forwardly from the forward side of the 65

front jaw 4 of the first elevator. The latch will be normally held by the spring 44 in the position shown in Fig. 3. During movement of the first elevator upwardly past the upper end of the lever 27, the pin 46 will ride 70 against the under side of the latch, the latter pivoting idly on its pivot 43 so that the upward movement of the first elevator does not alter the position of the lever 27, but during the descent of the first elevator from such an upper position toward its normal level, which occurs, as usual, after the line delivery slide has returned to its normal right hand position where it is retained until released by lifting of the assembling elevator, 75 as disclosed in said Mergenthaler patent, the pin 46 will bear on the upper side of the latch 42 and will swing it about its pivot 43 into the inclined position shown in Fig. 4, and if one of the pins 41 on the shaft 80 39 then occupies a position in the path of the latch 42, the swinging movement of the latter will be arrested while the portion of the latch engaged by the pin 46 is in inclined position, and further descent of the first elevator will 85 cause the pin 46 to have a cam action on the latch in a direction which will force the upper end of the lever 27 from its operative position as shown by the full lines in Fig. 1 into its inoperative position as shown by the 90 dotted lines in said figure.

The front jaw 4 of the first elevator also has a pawl 47 pivotally mounted thereon by the pivot pin 48, this pawl being thus pivoted to swing vertically and having a portion 47^a 100 which overhangs the top of the front vise jaw 4 so as to normally support the pawl in horizontal position as shown in Figs. 3 and 4. The free end of this pawl, during the vertical movements of the first elevator, travels in a path which is in line with a tooth of the ratchet wheel 38. In consequence, when the first elevator moves upwardly from its normal position, the free end of the pawl will act on the tooth of the ratchet wheel 38 which is in line therewith and will thereby rotate the shaft 39 one step, although when the first elevator returns to its normal level, the pawl 47 will ride idly past the wheel 38.

In the construction shown in Figs. 3 and 4, the number of pins 41 on the shaft 39 corresponds with the number of teeth on the ratchet wheel 38, and in consequence, when the lever 27 is set for recasting from an assembled line of matrices and spacers, two type bars or slugs will be cast from such line after which the casting operation will be automatically arrested, since the nose of the latch 42 will move into position above the pin 46 when the lever is swung into operative position and hence the said latch will not be acted on by said pin during the first descent of the first elevator to casting position but the first movement of the first elevator upwardly past its normal level following the first casting 115 120 125 730

operation will cause the pawl 47 to act on the ratchet wheel 38 to carry the pin 41 previously engaged by the latch 42 out of the path of the latch and to bring the next pin on the shaft 39 into position to be engaged by the latch 42 so that on the second descent of the first elevator to casting position, following the first casting operation, the latch 42 will be blocked in its swing under the action of the descending pin 46 as shown in Fig. 4, and in consequence, the lever 27 will be swung from its operative position shown by the full lines in Fig. 1 and the dotted lines in Figs. 3 and 4 into the position shown by the dotted lines in Fig. 1. While the lever 27 is in the full line position shown in Fig. 1, the toggle links 33 and 34 are locked as shown in Fig. 5, and the stopping means for the machine are thus inactive so that the casting operation may be repeated, but when the lever 27 is swung into the dotted line position shown in Fig. 1, the toggle links 33 and 34 are flexed or unlocked as shown by the dotted lines in Fig. 5, and the stopping means for the main cam shaft is then operative to stop the operation of the machine in the usual way when the cycle of operations has been completed.

The present invention enables any desired number of casts to be made from any assembled line of matrices and spacers by varying the number of pins on the shaft 39, it being obvious that by using a smaller number of pins than that shown in Figs. 3 and 4 a greater number of recasts may be made automatically from each line. For example, Fig. 6 shows the shaft 39 with three alternate pins removed so that it carries only three of the pins 41 while the ratchet wheel 38 has six teeth as in Figs. 3 and 4, and according to Fig. 6, three casts will be made automatically from each line during each casting operation, and by using two pins, four casts will be made automatically from each line during each casting operation. If desired, the shaft 39 may be provided with a single pin, in which event, said shaft could be set to cause any predetermined or desired number of casts to be made from a line during each casting operation of the machine before the operation of the machine is automatically arrested, the shaft 39 being set back after the last recasting operation so that it will then be in proper position to recast the next line.

In order to prevent removal of the assembled line of matrices and spacers from which a recast is to be made, upon ascent of the first elevator following the first casting operation, means is provided for preventing ascent of the first elevator to its full uppermost position. Such means comprises a screw 49 adjustably mounted in an arm 50 which projects rigidly forwardly from the lower end of the first elevator slide so that the screw will be in line with and will engage in a seat or recess 51 in the lower end of the lever 27 when

the latter is set in its operative position for recasting, as shown by the full lines in Fig. 1. The engagement of the screw 49 with the lower end of the lever 27 arrests the upward movement of the first elevator toward its uppermost level, the excess motion of the elevator lifting lever 15 being absorbed by the spring cushion 16, and the line transfer slide 12 is preferably provided with a latch 52 such as that shown in U. S. Letters Patent No. 1,168,244 granted Jan. 11, 1916, to W. E. Bertram, this latch automatically holding the transfer slide 12 in its retracted or inactive position since the first elevator will not rise sufficiently to trip the latch. While the lever 27 is in its inactive position as shown by the dotted lines in Fig. 1, the screw 49 will clear the lower end thereof so that the first elevator will be permitted to rise to its full extent, thereby tripping the latch 52 and allowing the transfer slide 12 to remove the assembled line of matrices and spacers from the first elevator, following completion of the casting operation with respect to such line.

The operation is as follows:—While the arm 29 is in its raised or inoperative position, the machine will operate in the usual way, casting one type bar or slug from each assembled line of matrices and spacers, since the lever 27 will not be shifted into active position by the movement of the line delivery slide 10, and hence the starting and stopping bar 24 will not be held forward to prevent stopping of the machine in the usual way upon completion of a single casting operation, and the first elevator will be permitted to rise to its full height for the removal of the line of matrices and spacers therefrom and the latch 52 will be tripped to allow the transfer slide 12 to operate to remove the line from said elevator in the usual way, following the casting of a single type bar or slug therefrom.

When it is desired to cast two or more type bars or slugs from any one or all of the assembled lines of matrices and spacers composed in the machine, it is only necessary to swing the arm 29 on the line delivery slide 10 downwardly or forwardly so that its path of movement during the line delivery stroke of the slide 10 will carry it against the upper end of the lever 27. When the arm 29 is so set, the stroke of the slide 10 in delivering the line of assembled matrices and spacers into the first elevator will swing the lever 27 from the dotted-line position to the full-line position shown in Fig. 1, thereby locking the toggle 33, 34 to hold the bar 24 in a position which will prevent stopping of the machine after one cast has been made from the line, and bringing the lower end of the lever 27 into position opposite to the screw 49 to prevent rising of the first elevator fully to line delivery position so that the

latch 52 will not be tripped but will hold the delivery slide 12 against movement to remove the line from the first elevator, so that the line will remain therein ready to be again lowered to casting position for casting another type bar or slug therefrom. At the same time, the ratchet 38 and latch 42 on the upper end of the lever 29 will be brought into the paths of the pawl 47 and pin 46 respectively on the first elevator as shown in Fig. 3, so that the descent of the first elevator from its normal or line receiving position to casting position for the first casting operation will cause the pin 46 to descend without affecting the latch 42 but the first upward movement of the first elevator past its normal or line receiving position, following the first cast from the line, will cause the shaft 39 to rotate one step which, according to the construction shown in Figs. 3 and 4, will bring another pin 41 into engaging or blocking relation with the latch 42, so that the next following descent of the first elevator to lower the line to the casting level for the second or next following cast will cause the descending pin 46 on the first elevator to cam on the inclined upper side of the latch 42 while the latter is blocked by the latter pin, as shown in Fig. 4, and the lever 27 will be thrown into inoperative position shown by the dotted lines in Fig. 1. After the second cast has been made from the line, the first elevator rises, and since the lower end of the lever 27 is then clear of the path of the screws 49, the first elevator will rise to its full height, tripping the latch 52 and allowing the delivery slide 12 to remove the line therefrom in the usual way, and since the throwing of the lever 27 into inoperative position breaks or unlocks the toggle 33, 34, the bar 24 will no longer be held in a position to prevent stopping of the machine and hence the machine will be stopped automatically after completion of the second casting operation.

In order to automatically cast more than two type bars or slugs from an assembled line of matrices and spacers, it is only necessary to employ a fewer number of pins on the shaft 39. For example, in Fig. 6 wherein the number of pins 41 is equal to only one half the number of teeth on the ratchet wheel 38, the first elevator will move upwardly past its normal or line receiving position twice before a pin is brought into position to block the latch 42 and thereby cause throwing of the lever 27 into inoperative position upon the third descent of the first elevator to casting position, and consequently, three type bars or slugs will be cast from the line before the casting operation for that line is completed and terminated and such line is removed from the first elevator. Obviously, by providing only one pin on the shaft 39, any desired number of recasts up to the num-

ber of teeth on the ratchet wheel 38 may be made from any matrix line by appropriately setting said shaft rotatably to position the pin at different distances away from its engaging position with the latch 42 prior to the commencement of each series of casting operations.

From the foregoing, it will be seen that the present invention enables the machine to be easily and quickly set by the operator, while occupying his usual position in front of the machine, to cast either a plurality of type bars or slugs from any or all of the matrix lines composed in the machine or to cast a single type bar or slug from each matrix line, as may be desired by simply setting the arm 29 on the line delivery slide accordingly, the setting of this arm performing the dual function of bringing the recasting means into operation which causes continued operation of the machine until the desired number of casts have been made and also retaining the matrix line in the first elevator until such casts have been completed, whereupon the stopping mechanism of the machine is automatically brought into condition to stop the machine and the line is removed from the first elevator.

The recasting control, it will therefore be clear, is effected by the setting of the arm 29 in operative or inoperative position. When said arm is set in operative position the line will be recast, and if said arm is permitted to remain in operative position, the machine will operate automatically to make a predetermined number of recasts from each matrix line introduced into the first elevator before removing such line therefrom, but the recasting operation of the machine will be interrupted by the setting of the arm 29 in inoperative position, the machine being then restored to the normal condition so that it will operate in the usual way to make a single cast from each matrix line.

It is to be understood that in operating a typographical machine of the class referred to and equipped with recasting control means as hereinbefore described, the matrices and spacers are assembled in a line in the assembling elevator which is then raised to bring the line into position for delivery by the line delivery slide to the first elevator following which the line delivery slide returns to its normal right hand position where it is held until released by lifting of the assembling elevator in the usual manner, and that the next following matrix line is not sent into the first elevator until the recasting of the preceding line has been completed, any suitable means being employed on the machine for preventing the sending of another line into the first elevator while recasting of the preceding line is taking place. For example, as shown in the present instance, a lever 53 may be pivoted at 54 to the transfer channel 13,

the upper arm of this lever having a finger 55 which is in the path of the first elevator and in position to be engaged and lifted thereby when it reaches its uppermost or line removing position, the lower arm 56 of this lever normally overlying the assembling elevator 1 while in its normal lowered position to prevent lifting thereof, and a pin 57 is secured to the line delivery carriage 10 in a position to engage the lower arm of the lever 53 when the line delivery carriage returns to its normal line receiving position, the pin 57 acting to swing the lower arm 56 of the lever 53 into position above the assembling elevator. In operation, when the first elevator approaches its uppermost or line removing position following completion of the last recasting operation, the full ascent of the first elevator being then permitted by the lever 27 which will then be swung clear of the stop 49, the finger 55 on the upper arm of the lever 53 will be swung upwardly by the first elevator, thereby swinging the lower arm of the lever 53 from above the assembling elevator so that the latter may be lifted to introduce another matrix line into the line delivery carriage 10 for transfer to the first elevator, and upon the return of the line delivery carriage to normal position after introducing the line into the first elevator, the pin 57 will engage the lower arm 56 of the lever 53 and swing its lower end into position above the assembling elevator and thereby prevent lifting of another line into the line delivery carriage. The lever 53 will remain in locking relation with the assembling elevator while the desired number of casts are being made from the preceding matrix line, since the lever 27 will be in a position to prevent ascent of the first elevator to its uppermost point where it engages the finger 55 on the lever 53 until the last recast has been made whereupon it is moved into normal or inactive position in the manner hereinbefore described, it then permitting full ascent of the first elevator and movement of the lever 53 into position to release the assembling elevator, as stated above.

I claim as my invention:

1. In a typographical machine embodying a member to receive a line of matrices and spacers, means for removing said line therefrom, and means normally operative to move said member into position to present the line to a mold for casting a type slug therefrom and then into position for removal of the line therefrom, a device capable of being set to prevent removal of the line from said member and to cause said member to present the line a plurality of times to casting position.
2. In a typographical machine embodying a member to receive a line of matrices and spacers, means for delivering a line thereto, means for removing the line therefrom, and means normally operative to move said mem-

ber to convey the line from line-receiving position to a casting position and from the latter position to line-removing position, a device controlled by the line delivering means for preventing removal of the line from said member by said line removing means and for causing said member to bring the line successively to the casting position.

3. In a typographical machine embodying a member to receive a line of matrices and spacers, means for removing the line therefrom, and means for moving said member to bring the line to casting position and then to line removing position, including means for stopping the movement of said member, a device capable of being set to prevent removal of the line from said member and to control said stopping means to prevent stopping of said member.

4. In a typographical machine embodying a member to receive a line of matrices and spacers, means for delivering a line thereto, means for removing the line therefrom, and means normally operative to move said member to carry the line from line-receiving position to a casting position and from the latter position to line-removing position, including means for stopping the movement of said member after removal of the line therefrom, a device capable of being set for operation by the line delivering means to prevent removal of a line from said member and to control said stopping means to prevent stopping of said member.

5. In a typographical machine embodying a member to receive a line of matrices and spacers, means for removing the line therefrom, and means including a stopping element normally operative to move said member to carry the line into casting position and then into line removing position and for subsequently stopping the movement of said member, a device operative to prevent removal of the line from said member upon reaching line removing position and to control said stopping element to prevent stopping of said member, and means controlled by said member for rendering said device inactive after said member has carried the line a plurality of times into casting position.

6. In a typographical machine embodying a member to receive a line of matrices and spacers, means for delivering a line to said member, means for removing a line therefrom, and means including a stopping element for normally moving said member to carry the line into casting position and then into line removing position and for subsequently stopping the movement of said member, a device capable of preventing removal of the line from said member and of preventing stopping thereof, means operative by the line delivering means for bringing said device into operation, and means controlled by said member for rendering said device inoperative.

7. In a typographical machine embodying a member movable to carry a line of matrices and spacers into line receiving, casting and line removing positions, line transfer and delivery slides cooperative therewith, and means including a stopping element for normally moving said member to carry the line successively into said positions and then stopping its movement, means set into position by the line delivery slide to hold said stopping element against operation. 75
8. In a typographical machine embodying a member movable to carry a line of matrices and spacers into line receiving, casting and line removing positions, line transfer and delivery slides cooperative therewith, and means including a stopping element for normally moving said member to carry the line successively into said positions and then stopping its movement, means set into position by the line delivery slide to hold said stopping element against operation and set into inoperative position by said member to release said stopping element for operation. 80
9. In a typographical machine embodying a member movable to carry a line of matrices and spacers into line receiving, casting and line removing positions, line transfer and delivery slides cooperative therewith, and means including a stopping element for normally moving said member to carry the line successively into said positions and then stopping its movement, means set into position by the line delivery slide to hold said stopping element against operation, and means controlled according to the number of movements of said member into casting position for setting said device into position to release said stopping member for operation. 95
10. In a typographical machine embodying an elevator, a delivery slide for introducing a line of matrices and spacers therein, and means including a stopping element for moving the elevator to carry the line into casting position, a member connected to said stopping element, and a part actuated by the delivery slide and capable of being set to actuate said member to hold the stopping element against operation. 100
11. In a typographical machine embodying an elevator to hold a line of matrices and spacers, a slide for removing the line therefrom, and means including a stopping element for normally moving the elevator to bring the line to casting position and then to line removing position, a member having means to act on said stopping element to hold it against operation and also having means for preventing removal of the line from the elevator when said member is in active position, a latch on said member, a part carried by the elevator and movable idly past the latch during movement of the elevator in one direction, and means for holding the latch against movement relatively to said member 115
- while engaged by said part during movement of the elevator in the opposite direction for moving said member out of active position. 120
12. In a typographical machine embodying an elevator to hold a line of matrices and spacers, a slide for removing the line therefrom, and means including a stopping element for normally moving the elevator to bring the line to casting position and then to line removing position, a member having means to act on said stopping element to hold it against operation and also having means for preventing removal of the line from the elevator when said member is in active position, and means operative by the movements of the elevator and capable of being set to render said member inactive after the elevator has brought the line a predetermined number of times to casting position. 125
13. In a typographical machine embodying an elevator to hold a line of matrices and spacers, means for removing the line therefrom when the elevator reaches line-removing position, and means including a stopping element for normally moving the elevator to bring the line to casting position and then to line removing position, a member connected to said stopping element and movable into position to hold said element against operation and to bring a part thereof into the path of the elevator to prevent its movement into line-removing position. 130
14. In a typographical machine embodying an elevator to hold a line of matrices and spacers, means for removing the line therefrom when the elevator reaches line-removing position, and means including a stopping element for normally moving the elevator to bring the line to casting position and then to line removing position, a member connected to said stopping element and movable into active position to hold said element against operation and to bring a part thereof into position to prevent movement of the elevator into line-removing position, a latch pivoted on said member, a projection on the elevator engageable with said latch, a shaft rotatably mounted on said member and having pins projecting therefrom to engage the latch and prevent its movement in one direction under the action of said projection on the elevator and thereby cause movement of said member into inactive position, a toothed member connected to said shaft, and a pawl carried by the elevator and cooperative with said toothed member to rotate it and said shaft to bring a pin on the latter into engaging relation with said latch. 135
15. In a typographical machine embodying a member to receive a line of matrices and spacers, and operating means for normally moving said member successively into line receiving, casting and line removing positions, means including an element containing a changeable number of pins for causing 140

said operating means to move said member to present the line a selected number of times to casting position.

16. In a typographical machine embodying a member to receive a line of matrices and spacers, means for introducing the line therein, means for removing the line therefrom, and operating means for normally moving said member successively into line receiving, casting and line removing positions, means capable of being set to prevent movement of said member into line removing position, and means for preventing introduction of another line into said member, said latter means being rendered inactive by the movement of said member into line removing position.

In testimony whereof I have hereunto set my hand.

20 SAMUEL E. SPERRY.
